UNITED STATES PATENT OFFICE.

EMMA DAMRAU, OF NEW YORK, N. Y.

CURTAIN-SUPPORT.

SPECIFICATION forming part of Letters Patent No. 659,018, dated October 2, 1900.

Application filed July 12, 1900. Serial No. 28,349. (No model.)

To all whom it may concern:

Be it known that I, EMMA DAMRAU, a citizen of the United States, residing at New York, (Brooklyn,) in the county of Kings and State 5 of New York, have invented certain new and useful Improvements in Curtain-Supports, of which the following is a full and complete specification, such as will enable those skilled in the art to which it appertains to make and 10 use the same.

This invention relates to means for supporting curtains, portières, and similar articles; and one object thereof is to provide an improved device of this class which is particularly designed for use for supporting window-curtains, but which may be used when desired for supporting various other articles of this class, a further object being to provide a device of the class described which 20 will support a curtain, portière, or similar other article without the use of pins, hooks, or other fastening devices.

This invention is fully disclosed in the following specification, of which the accompanying drawings form a part, in which the separate parts of my improvement are designated by the same reference characters in each of the views, and in which—

Figure 1 is a front view of the upper portion 30 of a window-frame provided with my improved curtain-holder; Fig. 2, a plan view of the holder detached and on an enlarged scale; Fig. 3, a section on the line 3 3 of Fig. 1 and on an enlarged scale; Fig. 4, a section on the line 4 4 of Fig. 2 and on an enlarged scale; Fig. 5, a plan view of a detail of the construction, which I employ; Fig. 6, a view similar to Fig. 1, showing a modification; and Fig. 7, a section on the line 7 7 of Fig. 6 and on 40 an enlarged scale.

In the drawings forming part of this specification I have shown at A the upper portion of a window-frame, and in the practice of my invention I secure thereto at the opposite 45 sides and near the top thereof two brackets B and mount therein a pole C of the usual form. The pole C is provided at one side (the front side as shown in the drawings) with two socket-plates D, one of which is shown 50 in detail in Fig. 5, and these socket-plates are provided at opposite points with projections d, through which screws are passed to secure

them to the pole, and the said socket-plates are provided centrally with screw-threaded sockets, the opening to one of which is shown 55 at d² in Fig. 5, and in practice I pass through the arms b of the bracket B a screw E, and the screws E enter the sockets in the socket-plates D and securely hold the pole C and prevent it from turning. One of the socket-plates D is shown in dotted lines in Fig. 3, as is also the screw-threaded socket d², connected therewith.

I also provide two socket-plates F, which are exactly similar to the socket-plates D 65 and are connected with the back of the pole at f in the same manner as the socket-plates D, and in connecting the curtain or other article with the pole I provide a bar G and a supplemental bar H, through which are 70 passed screws h. The bars G and H are preferably composed of metal and may be of any desired thickness, and the curtain or portière is passed upwardly between the bar G 75 and the pole C, and the upper end thereof may be folded over forwardly in front of said pole or downwardly and backwardly over the bars G and H. The bar H is also provided with a plurality of screws h², which are passed therethrough and which bear on the bar G 80 and press said bar against the curtain or portière and against the pole C, and the said curtain or portière is thus securely held in place without the use of pins, hooks, or other fastening devices.

The socket-plates D are not shown in section; but it will be understood that they are of the same form and construction as the socket-plates F, which are clearly shown in section.

In Fig. 6 I have shown my improvement applied to what is known as a "canopy" support or holder for curtains, portières, and similar articles, and in this construction I provide a canopy K of the usual or any preferred form, which is secured to the window-frame transversely of the top thereof, and the said canopy is open at the bottom, as shown at k, and provided with a front wall k², and the front wall k² takes the place of the pole 95 C, and the bar G is connected with said front wall k² of the canopy K in the same manner as it is connected with the pole C when the latter is employed, and the screws h² are em- 100

ployed in connection with the bar H also in the same manner as hereinbefore described.

It will be understood that in the form of construction shown in Figs. 1, 2, and 4 the bar G is free to move on the screws h, and this same construction, although it is not shown in detail, is employed in Figs. 6 and 7, and the bar H is also free to move on the screws h, while the screws h² serve to press the bar G firmly against the pole C and against the front wall k² of the canopy K. I have also shown at L, both in Figs. 1 and 7, a portion of a curtain, which is supported in the manner described, and in Fig. 7 the upper end of the curtain is shown as passed up between the front wall k² of the canopy and the bar G, and in Fig. 1 the curtain is shown as passed up over the pole C and down between said pole and the bar G.

My improved support for curtains, portières, and the like is simple in construction and operation and perfectly adapted to accomplish the result for which it is intended, and it will be apparent that changes in and modifications of the construction described may be made without departing from the spirit of my invention or sacrificing its advantages.

Having fully described my invention, I claim as new and desire to secure by Letters Patent—

1. A support or holder for curtains, comprising a stationary member, a bar movably connected with one side thereof, and a supplemental bar movably mounted rearwardly of the first-named bar, and set-screws which are passed through the supplemental bar and adapted to bear on the first-named bar, substantially as shown and described.

2. A curtain-pole which is adapted to be mounted in brackets and provided with devices for preventing it from turning therein, a bar connected at its opposite ends with the

rear side of said pole, and between which and said pole the curtain is adapted to be passed, 45 a supplemental bar also connected at its opposite ends with the rear end of said pole rearwardly of the first-named bar, and adjusting devices which are passed through said supplemental bar and adapted to bear on the 50 first-named bar, substantially as shown and described.

3. A curtain-pole provided with socket-plates which are secured in the front side thereof near its opposite ends, and other 55 socket-plates which are secured in the rear side thereof adjacent to its opposite ends screws passed into the sockets in the last-named plates, a bar connected with the rear side of said pole by said screws which are 60 passed through the opposite ends thereof, and a supplemental bar also mounted on said screws rearwardly of the first-named bar, and provided with set-screws which are passed therethrough and which are adapted to bear 65 on the first-named bar, substantially as shown and described.

4. A curtain or portière holder, comprising a stationary member, provided adjacent to its opposite ends with supporting devices a 70 bar movably mounted on said devices, a supplemental bar also movably mounted on said devices rearwardly of the first-named bar and set-screws which are passed through the supplemental bar and adapted to press upon 75 said first-named bar and to force the latter against the stationary member, substantially as shown and described.

In testimony that I claim the foregoing as my invention I have signed my name, in presence of the subscribing witnesses, this 11th day of July, 1900.

EMMA DAMRAU.
